UNITED STATES PATENT OFFICE

MICHAEL G. STOLLER, OF PAULDING, OHIO

RAILROAD CROSSING

Application filed May 10, 1930. Serial No. 451,431.

This invention relates to railway crossings, the primary object of the invention being to provide continuous rails at railway crossings, eliminating the usual gaps or spaces between the ends of adjacent rails of crossings.

An important object of the invention is to provide a device of this character which may be controlled by an operator from a point remote from the crossing, the device comprising vertically movable rail sections movable between the ends of the rails.

A still further object of the invention is to provide a device of this character which will be protected against snow and ice, to the end that the device will operate at all times.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a plan view of a railway crossing equipped with movable rail sections or blocks, constructed in accordance with the invention.

Figure 2 is a sectional view taken on line 2-2 of Figure 1.

Figure 3 is a transverse sectional view through the supporting members or chairs supporting the rails of the crossing.

Figure 4 is a transverse sectional view through the crossing, illustrating the movable rail sections at the opposite side of the crossing.

Figure 5 is a vertical sectional view through one of the movable rail sections or blocks and its operating wedge.

Figure 6 is a sectional view taken on line 6-6 of Figure 4.

Figure 7 is a sectional view taken on line 7-7 of Figure 1.

Figure 8 is a sectional view taken on line 8-8 of Figure 1.

Referring to the drawings in detail, the reference character 5 designates the inner rails of a railway crossing, and the reference character 6 designates the guard rails thereof. The reference character 7 designates rail sections of the crossing that extend at right angles to the rails 5, the rails 5 and 7 being connected at their ends.

The reference character 8 designates the guard rails for the rail sections 7. Guard rails 9 form a part of the crossing and are spaced from the rails 10 that form continuations of the track. The rails 11 form continuations of the track sections 7 and extend in opposite directions from the rail sections 5, the rail sections 11 being spaced from the guard rails 12 that extend in parallel relation with the rail sections 11.

The track rails and guard rail sections are cast integral with the chairs 13, which chairs are embedded in the track bed to insure against movement thereof. Bores 14 extend transversely through the chairs 13, and intersect longitudinal bores 15, at points intermediate the ends of the bores 15.

Operating wedges 16 are mounted for sliding movement in the openings 14 and 15, the wedges 16 being provided with lateral ribs 17 disposed along the upper edges thereof, the ribs operating in grooves formed in the rail sections or blocks 18, so that sliding movement of the wedges 16 will produce a vertical movement of the rail sections or blocks 18 to move them to their active or inactive positions.

Thus it will be seen that due to this construction, rail sections or blocks are provided at each corner of the railway crossing, and that by moving the wedges 16, the rail sections or blocks may be moved so that the upper ends thereof are flush with the surfaces of the adjacent ends of rail sections forming a railway crossing, providing a continuous track.

Supported between the rail chairs are beams 19 that are spaced apart, the beams being connected by means of a transverse bar 20 disposed intermediate the ends of the beams 19. These beams 19 provide a support for the operating mechanism, which includes two independent sets of levers, one set of levers be-

ing designed to operate the rail sections or blocks at one side of the crossing, while the other set of levers operates the rail sections or blocks at the other side of the crossing.

5 In describing the set of levers as shown by Figure 4 of the drawings, it will be seen that the wedges 16 are provided with extensions to which the rods 21 are connected, the rods 21 having their inner extremities pivotally connected to the arms 22 of the bell crank levers 23 at opposite sides of the crossing, the inner arms 24 of the bell crank levers being pivotally connected to the links 25 and 26 respectively. As clearly shown, one of the links 26 10 connects with the pivoted arm 27, the opposite link 26 being connected to one end of the pivoted arm 27 which is mounted directly under the arm 35.

15 The link 25 connected with one of the arms 24 connects with one end of the arm 27 at 29, 20 while the opposite link 25 connects with the opposite end of the arm 28, at 30. The reference character 31 designates operating rods that have pivotal connection with the bell 25 crank levers, at their inner ends, the opposite ends of the rods being connected with the operating rod 32 which extends along the track and is provided with means whereby the rods 31 and 32 may be operated to move 30 the bell crank levers, links and arms connected therewith, for operating the wedges 17 and rail sections 18 connected therewith.

25 The rail sections or blocks at the opposite sides of the crossing are operated by the bell crank levers 33 and 34 respectively, the levers 33 being connected with the rods 33' that connect with certain rail sections, while the levers 34 connect with similar rods 34', disposed directly thereunder.

30 The bell crank lever 33 at one side of the crossing is connected to the bar 35, by means of the link 36, the opposite bell crank lever 33 being connected to the pivoted bar 37 mounted directly under the bar 35, by means 35 of the link 38. One of the bell crank levers 34 connects with one end of the pivoted bar 37, by means of the link 39, while the bell crank lever 34 at the opposite side of the crossing connects with the pivoted bar 35, through the medium of the link 40. Rod 41 connects with the bell crank lever 33, while the rod 42 connects with one of the bell crank levers 34. An operating rod 41' has connection with the rods 41 and 42 so that as the operating rod and 45 rods 41 and 42 are moved, the bell crank levers and wedges will be moved to operate the rail sections or blocks movable between the adjacent ends of the rails forming the crossing of the track.

50 In the use of the device, assuming that a train is moving in the direction of the arrow as shown by Figure 1 of the drawings, the operator will move the rods 31 in the direction indicated by the arrow A, as shown by Figure 1 of the drawings, whereupon the rods 21 will

be moved outwardly, causing the wedges to slide under the rail sections 18 as shown by Figure 4, moving them upwardly until the upper edges thereof lie flush with the upper edges of the rail sections associated therewith, 70 providing a smooth surface to be engaged by the wheels of the rolling stock moving thereover.

75 It is obvious that when a train moves over the crossing in the opposite direction, the rods 31 are moved in the opposite direction to lower the rail sections, and the operating rods at the opposite side of the crossing will be moved to move the bell crank levers and links associated therewith, to elevate the rail sections or blocks at the opposite side of the crossing, 80 providing a smooth crossing and eliminating the usual pounding caused by a train moving over the spaces between adjacent ends of the rails of a track.

85 I claim:

In a railway crossing, rail chairs having bores extending horizontally therethrough, said railway chairs having vertical openings, vertically movable rail sections operating in the vertical openings, said rail sections having grooves in the lower ends thereof, wedge shaped members mounted in the horizontal bores, the upper edges of the wedge shaped members being inclined and positioned in the grooves of the rail sections, and levers for operating the wedge shaped members.

90 In testimony that I claim the foregoing as my own, I have hereto affixed my signature.

95 MICHAEL G. STOLLER.
